UNITED STATES PATENT OFFICE

SAMUEL N. McCLEAN, OF CLEVELAND, OHIO.

BREECH-LOADING ORDNANCE.

No. 800,757.

Specification of Letters Patent.

Patented Oct.

Application filed October 5, 1901. Serial No. 77,720.

To all whom it may concern:

Be it known that I, SAMUEL N. McCLEAN, a resident of Cleveland, Ohio, have invented a new and useful Improvement in Breech-Loading Ordnance, which is fully set forth in the following specification.

My invention relates to breech-loading ordnance, and has for its object to provide a breech mechanism and means for operating the same to open and close the breech, which means, together with said breech mechanism, shall be embodied in the fewest possible number of parts, easily manufactured at a minimum cost, accurate and reliable in operation, and not liable to get out of order.

A further object is to provide a gun which shall possess certain military advantages in that the manual of loading and firing the gun shall consist of but few and simple movements, while the gun by reason of its simplicity of construction may be easily and quickly assembled and disassembled for inspection or cleaning or for the purpose of disabling the gun in cases of emergency or threatened capture by an enemy.

With these objects in view the invention consists in a gun having screw-threaded breech-block and a carrier therefor, one of which parts is provided with an annular way in a plane at right angles to the axis of the block and the other with a wing or lug entering said way to the end that said block and carrier may constitute a motor when power is admitted thereto for operating the block to open and close the breech.

The invention further consists in a breech-block carrier and a carrier-supporting bracket so constructed and arranged with relation to each other that they become a motor for swinging the carrier from and to the breech of the gun to open and close the breech.

Furthermore, the invention consists in a gun having a screw-threaded breech-block, a breech-block carrier, and a carrier-supporting bracket all so combined as to constitute two motors which act successively to unlock the breech-block and swing it from the gun and to return and relock it again when the flow of the motive fluid is reversed through the motors by suitable means provided for that purpose. Any suitable source of motive power may be employed without departing from the broad features of the invention mentioned above; but I prefer to utilize the energy due to the discharge of the gun, and in

the preferred form of the invention illustrated the power utilized for the motors is that due to the energy stored in the recoil-cylinders, and it is transmitted from the non-recoil cylinders on the carriage to the motors upon and recoil with the gun in the motor fluid under pressure, which is transmitted from the recoil-cylinders by means of rigid piping instead of flexible hose connections. This rigid connection is in the hollow piston-rod connected to the piston of the recoil-cylinder and to the gun and from a point within the cylinder to the operating the breech mechanism. Such fluid may be of any desired description in the construction herein shown it is oil or glycerin with which the recoil-cylinder is filled, a spring being employed to gun to battery after recoil and place glycerin under pressure. It is obvious air might be employed as a substitute for the spring and oil, and if so used the be the mechanical equivalent of the oil. By preference two cylinders and piston-rod are employed, the passages connecting the cylinders at opposite ends and with a piston and rod in each cylinder, the motive fluid taken through one piston-rod to the cylinder and returned through the other piston-rod which latter thus becomes the means for conveying the exhaust fluid back to the cylinder for further use. The flow of the motive fluid to the motor or motors for operating the breech mechanism is controlled by a valve by operating which the motive fluid through the motor or motors may be reversed so as to open or close the breech as may be desired. This valve may be actuated manually, and an operating-hand lever is provided for that purpose; but I prefer to have it automatically, and for this purpose I provide means for operating the valve by it is turned during recoil in a position to close the breech, the valve-operating means then held against reverse action, with the valve to close the breech until the discharge of the charge, which latter automatically actuates a part (preferably the ejector) of the valve-operating means and permits the valve to be shifted into position to close the breech.

The invention also consists in certain details of improvement, which will be

scribed and then pointed out in the

of course be understood that parts invention may be employed without the whole and that the inventive idea may receive various mechanical ex-

s. for the purpose of illustration shown accompanying drawings one of the which the invention may assume; but be understood that such drawings are d for illustration only and not as de- e limits of the invention.

drawings, Figure 1 is a transverse plan of the breech of the gun, the lock being shown in full. Fig. 2 is f the breech end of the gun with the closed. Fig. similar diagrammatic view with the pen and before a charge has been in- he valve being in position to open

Fig. 18 is a detail of the ejector. s a detail of the ejector and the catch strains the valve-operating rack, and s a further detail of the same. ing to the drawings, 1 is a gun mount- le in a cradle 2, which latter is held earward movement on any suitable

Supported under the cradle 2 are il-cylinders 3 and 4, within which are and 6, having hollow piston-rods 7 ending rearward through the ends of eactive cylinders 3 and 4 and secured , depending from and rigidly secured each end of the gun. Springs 10 and laced in the cylinders 3 and 4 be- e pistons 5 and 6 and the rear ends of ders, which latter are filled with any liquid, as oil or glycerin, and are

provided with connecting passages 12 and 13 between their respective ends. The pistons 5 and 6 are provided with suitable openings 14 and 15, passing from the front to the rear face of the piston and controlled by valves 16 70 and 17, which open as the pistons move rear- ward upon recoil, but close when the pistons move forward under the influence of their springs. The hollow piston-rod 7 opens into the cylinder 3 at 18 on the rear side of the 75 piston 5, and the rod 8 opens into the cylinder 4 at 19 on the front side of the piston 6. The piston-rods 7 and 8 are firmly secured to the lug 9 by nuts 20 or other means, so that they are compelled to partake of all of the 80 backward and forward movements of the gun.

The breech-block 21 is here shown as of the conical continuously-threaded type and has a rear part 22, around which is cut an annular groove or way 23 in a plate at right angles 85 to the axis of the block, and this groove is filled for a portion of its length, as at 24. For convenience of manufacture I prefer to cut the groove or way as a complete annular groove and then insert the part 24, as shown; 90 but such part 24 may, if desired, be integral with the block. For the purpose of lightening the block and housing the firing mechanism the block may be hollowed out, as at 25. A breech-block carrier 26 is mounted to turn on a 95 bracket 27 at one side of the breech end of the gun. This carrier 26 is in the form of a cylinder or cup open at its forward end and embracing the rear portion of the breech-block 21 and provided with an inwardly-projecting wing or 100 lug 28 on its interior surface, (see dotted lines, Fig. 3,) which enters and forms a fluid-tight fit in the groove or way 23 on the block. To enable the breech-block and carrier to be conveniently assembled, the wing or lug 28 is 105 formed separate from the carrier, and in as- sembling the parts the lug 28 is placed in the groove 23 in the breech-block, after which the block is slipped into place in the carrier and the lug 28 secured to the carrier by suitable 110 means, as a screw, as clearly shown in Fig. 3. If desired, a packing-ring 29 may be employed to effect a fluid-tight joint between the breech- block and the carrier. The bracket 27 is firmly 115 secured to one side of the gun-breech and has a partially-cylindrical portion 30, having a cylindrical opening 31 therethrough and a vertically-extending rib 32, Fig. 1, on its outer surface. Fitting tightly within opening 31 is a valve-casing 33, within which is a valve 120 composed of a sleeve 34 and a valve-stem 35, which sleeve and stem are mounted to turn in the casing 33, and will hereinafter be referred to as the "valve." The valve-casing 33 ex- tends below the bracket, as shown in Figs. 3 125 and 4, and the piston-rods 7 and 8 are connected thereto. That portion 36 of the car- rier 26 which engages the bracket 27 is par- 130 tially cylindrical and has top and bottom flanges 37 and 38, which embrace the valve-

casing 33. On the inside, top, and bottom surfaces of the flanges 37 and 38 are cut grooves 41 and 42, preferably concentric with the valve-casing 33, and the part 36 on the carrier also has an inwardly-projecting vertically-extending lip or rib 43 at one end and a like lip or rib 44 at the other end, and when the carrier and bracket are assembled the rib 32 on the bracket lies between the ribs 43 and 44 on the carrier, so that said ribs 32, 43, and 44, together with the outer surface of the part 30 of the bracket 27 and the inner surface of the part 36 of the carrier, constitute closed motor-chambers 45 and 46.

15 The chamber formed by the groove 23 in the breech-block and the walls of the carrier constitutes a motor for operating the block, while the chambers 45 and 46 together constitute a motor or pair of motor-chambers for 20 operating the carrier and for the purpose of controlling the flow of motive fluid to and from said motors the valve, composed of the sleeve 34 and stem 35, is placed in the valve-casing 33, so as to turn therein, the valve-casing, however, being tightly fitted in the opening 31 in the bracket, the fit being so close that the casing is not free to turn. The bottom of the casing is of greater diameter than the opening 31 in the bracket, (see Figs. 25 30 and 8,) and when the parts are assembled the casing is pushed up through the bracket and the lobes 37 38 on the carrier and a cap 47 screwed thereon, so that the valve-casing becomes the pintle around which the carrier 35 turns. The valve-stem has several grooves machined on its exterior surface and a central longitudinal passage 48 is formed therein. When the sleeve 34 is slipped over the stem, the grooves on the stem form passages into 40 which inlet and outlet ports are drilled at proper points. Passages are also formed through the valve sleeve and stem to the central passage 48. The groove 42 in the bottom lobe 38 of the carrier is divided into two parts by partitions 49 and 50, (see Figs. 7 and 14,) and the groove 41 in the upper lobe is similarly divided, and when the parts are assembled these grooves are covered by the outer portion of the hub 30 of the bracket, as 45 shown in Fig. 4. Fluid under pressure, which I shall call "power," is transmitted through the piston-rod 7 and vented through the piston-rod 8, which latter is in communication with the central passage 48 in both operative positions of the valve. That position 50 which the valve occupies when the breech is closed and the valve set to open it, as illustrated in Fig. 12, will first be described. Power is admitted by way of piston-rod 7 to port P and 55 passes along passage 51 on the valve, Figs. 8 and 12, to a port 52, which registers with a passage 53, formed entirely in the metal of the carrier and leading to the groove or way 23 in the breech-block at a point between the 60 partition 24 in said groove and the carrier. 65

abutment 28, which enters said groove the abutment 28 cannot turn, the a 24, and with it the breech-block, is turn from right to left for nearly a revolution, thereby disengaging the of the block from those on the gun. this movement of the part 24 the flu groove in front of the part 24 i through a passage 54, formed in the the carrier and leading from groove block to the forward division of gr Figs. 7 and 4, in the lower lobe 38 ir rier, and thence via port 55 to vent-p and piston-rod 8 to vent. The block c to revolve until the part 24 abuts the as shown in Fig. 13, when the pow via passage 56, Fig. 12, in the met carrier to the rear half of the groove of which it emerges through port 57 tor-chamber 45, and, pushing the 43 ahead of it, operates to swing th around and open the breech. While rier is swinging to open position th chamber 46, Fig. 1, is vented thro 58 and passage 48. When the c swung fully open, the pressure re chamber 45 and serves to retain it position until the valve is shifted fr tion shown in Fig. 12 to that of Fig. disconnects passage 51 from power nects passage 59, Fig. 13, with pc with chamber 46 via port 58 and also chamber 45 to vent via port 60, the 61, Fig. 8, being thrown out of regi the port 58 and the vent-port 62 being into register with port 60. Power is plied to and moves abutment 44 and rier to closed position, chamber 44 through port 60. Just as the carrie its closed position abutment 44 unco 63, Figs. 1, 8, and 13, which connects passage 64, Figs. 8 and 13, with the tion of groove 42 in lobe 38 of th and thence via passage 65, Fig. 1 metal of the carrier to passage 54, power is led into groove 23 on th block between abutments 24 and 28, and turning the block from left to ri screwing it home in the breech, duri the fluid in groove 23 in front of tment 24 is vented through passage groove 41 in the upper lobe of th and thence by passages 66 and 48 When the carrier is open, a tailpiece 1 and 7, on the abutment 44 acts to 63 to dust, &c.

Any suitable ejector device may be employed in guns using fixed ammunition for example, as that shown in Figs. wherein a lever 68 is pivoted in a n the gun and has a part 69 in the lug 70 on the carrier whereby the actuated by the carrier to eject the cartridge-shell. A handle 71 is at the valve-stem 35, whereby the v

ed by hand; but I prefer the construction of ejector and automatic valve-operating mechanism illustrated in Figs. 15 to 19. In this construction a mutiar 72 is attached to the valve and is and operated by a rack 73, having a spring 75, confined or recess 76 on the gun, the spring between the front end 77 of the box 78 on the rack-stem to force the rack rearward. The number of teeth on the valve are just sufficient to shift it the required distance. When the gun is in position, Fig. 15, a lug 79 on the rack is engaged by a spring-pressed lever 80, to a part 81 of the carriage, which recoil with the gun, and upon the lever 80 engages the lug 79 and the rack from moving rearward with thereby compressing the spring 75 and the rack 73 to turn the valve from the position of Fig. 15 to that of Figs. 17, at which instant a cam 82 on the lever 80 and depresses the engagement with the lug 79, (see Fig. 17,) and a pawl 84 on the gun enters a notch 85 on the rack and holds it in the tendency of its spring to force it forward. The valve is now, Fig. 16, in position to permit motive fluid to pass to the gun to open the breech, and this being accomplished the parts occupy the position shown in Fig. 17, in which the gun has moved so as to permit the cam 82 to free the lever 80 and allow it to again rise behind the lug 79, when the gun returns to battery.

Upon tripping the catch or pawl 84, the rack 73 is free to move rearward under tension of its spring from the position in Fig. 17 to that of Fig. 15, shifting the valve into position to close the breech. Any suitable tripping device may be employed to trip the catch 84; I prefer to utilize the extractor for this purpose.

The extractor 86, Figs. 18 to 20, is fitted in a recess formed in the breech of the gun and has a tail or arm extending exterior and in the path of a lug 87 on the carrier at the termination of its opening movement. The ejector has a slight bend beyond that of the lug 87 and has which as the ejector is in the act of moving rearward upon the insertion of the shell the tail of the catch 84 and lifts it from the notch 85, thereby freeing the rack. The ejector moves in the opposite direction to it does not actuate the catch 84, because its lower end has a knuckle-joint 89, which permits it to freely pass the gun without affecting it. The lug 87 on the carrier moves in a suitable slot cut in the carrier 90 on the bracket 27. Should it be necessary to trip the catch by hand without a charge, this may be done by a pressure on the lip of the extractor,

the slight freedom of movement between the tail of the extractor and the lug 87 being sufficient for this purpose.

What is claimed is—

1. In a gun, a breech-block-operating motor composed of a breech-block and a carrier embracing said block, one of said parts having a groove in a plane at right angles to the axis of the block and the other of said parts having a wing or lug fitting into said groove. 70

2. In a gun, a breech-block-operating motor composed of a breech-block having a circumferential groove formed therein in a plane at right angles to the axis of the block, and a wing or lug secured to the carrier and entering said groove in the breech-block. 80

3. In a gun, the combination of a breech-block having a motor groove or way formed thereon, a carrier embracing said block, and a wing or lug removably secured to the carrier and fitting into said groove, and means admitting a motive fluid to the groove. 85

4. In a gun, the combination of a breech-block having a rearwardly-projecting cylindrical portion, a circumferential groove on said portion in a plane at right angles to the axis of the block, a partition-wall or abutment in said groove, a carrier embracing said cylindrical portion and a wing or lug removably secured to the carrier and fitting into said groove, and means admitting a motive fluid to the groove. 90

5. In a gun, the combination of a breech-block carrier and a bracket on the gun pivotally supporting said carrier, said parts together constituting the walls of motor-chambers, whereby the carrier is swung to and from the breech of the gun. 100

6. In a gun, a carrier-operating motor composed of a bracket on the gun, and a carrier embracing the bracket and forming a motor-chamber between the walls of the bracket and carrier. 105

7. In a gun, the combination of a breech-block carrier, a bracket on the gun pivotally supporting the carrier, said parts together constituting the walls of motor-chambers operating to swing the carrier to and from the breech, and means in the axis of the carrier controlling the admission of motive fluid to said chambers. 110

8. In a gun, the combination of a breech-block carrier, a bracket on the gun having a partially-cylindrical hub or part around which the carrier swings, said hub and carrier constituting a motor-chamber for swinging the carrier, and a valve in the hub of the bracket and controlling the admission of motive fluid to said chamber. 120

9. In a gun, the combination of a breech-block, a carrier, and a bracket supporting the carrier, said block and carrier coacting as a motor to operate the block, and said carrier and bracket coacting as a motor to operate the carrier. 125

10. In a gun, the combination of a breech-block and a carrier one of which has a groove or way in a plane at right angles to the axis of the block and the other a lug or wing entering said groove or way and constituting a motor to operate the block, with a bracket on the gun to which the carrier is pivoted, the carrier and bracket constituting the walls of a motor-chamber for operating the carrier.
11. In a gun, the combination of a breech-block and a carrier one of which has a groove or way in a plane at right angles to the axis of the block and the other a lug or wing entering said groove or way and constituting a motor to operate the block, with a bracket on the gun, said bracket and carrier coacting as a motor to operate the carrier.
12. In a gun, the combination of a breech-block having a groove or way in a plane at right angles to the axis of the block, a carrier supporting the block and having a lug or wing entering said groove or way, a bracket on the gun having a hub-like portion which is embraced by the carrier to form a motor-chamber for operating the carrier.
13. The combination of a gun, a breech-block-operating motor carried thereby, a gun-carriage, a recoil-cylinder thereon constituting a source of motive fluid, a rigid pipe connection from said cylinder to one side of said motor, and a return-pipe from the other side of the motor to the cylinder.
14. The combination of a gun, a breech-block-operating motor carried thereby, a gun-carriage, a pair of recoil-cylinders thereon constituting a source of motive fluid, pistons in said cylinders, a hollow piston-rod connecting one piston to one side of said motor, and a second hollow piston-rod connecting the other piston to the other side of the motor.
15. The combination of a gun, a breech-block and carrier coöperating as a motor to operate the block, a bracket on the gun co-operating with the carrier as a motor to operate the carrier, a valve in the axis of the latter motor, a gun-carriage, a recoil-cylinder therein constituting a source of motive fluid and a pipe connection from said cylinder to said valve.
16. The combination of a gun, a breech-block and carrier coöperating as a motor to operate the block, a bracket on the gun co-operating with the carrier as a motor to operate the carrier, a valve in the axis of the latter motor, a gun-carriage, a pair of recoil-cylinders thereon constituting a source of motive fluid, a pipe connecting one of said cylinders to said valve, and a second pipe connecting the other cylinder to the valve whereby power is admitted from one cylinder to the motors through one pipe and exhausted through the other pipe to the second cylinder.
17. The combination of a gun, a breech-block and carrier coöperating as a motor to operate the block, a bracket on the gun co-
- operating with the carrier as a moderate the carrier, a valve in the latter motor, a gun-carriage, a pair of recoil-cylinders thereon constituting a source of motive fluid, a piston in each of said cylinders, a hollow piston-rod leading from one piston to said valve, and a hollow piston-rod leading from the rear of the gun to the valve, whereby power is admitted from one piston to the other.
18. The combination of a gun block carrier and its motor carried on a gun-carriage, a pair of recoil-cylinders thereon constituting a source of motive fluid in each of said cylinders, a hollow piston-rod leading from the front of one piston to one side of the motor, a hollow piston-rod leading from the other piston to the other side of the gun, whereby motive fluid is admitted through one rod and exhausted through the other.
19. The combination of a gun block and its operating-motor, a gun-carriage, a valve for reversing the operations of said motors, and means upon the insertion of the charge valve to close the breech.
20. The combination of a gun, block carrier pivoted thereon, a motor operating said carrier, a valve for admitting motive fluid to opposite sides of said motor carried by the gun for operating said device restraining said means from shifting when the breech is open, and a trip means from said restraining device shifting into position to close the breech.
21. The combination of a gun, block carrier pivoted thereon, a motor operating said carrier, a valve for admitting motive fluid to opposite sides of said motor, teeth on said valve, a spring-pressed by the gun and engaging said teeth, means checking the rearward movement of the rack and compressing its spring, recoil of the gun, whereby the valve is shifted to admit pressure to the motor to open the carrier, a check engaging to hold its spring compressed on the rearward movement of the recoil, and a trip for operating upon the insertion of the charge, whereby the valve is shifted to admit pressure to the motor to swing the carrier to the rearward position.
22. The combination of a gun, block carrier pivoted thereon, a motor operating said carrier, a valve for admitting motive fluid to opposite sides of said motor, teeth on said valve, a spring-pressed by the gun and engaging said teeth, means checking the rearward movement of the rack and compressing its spring on the rearward movement of the gun, whereby the valve is shifted to admit pressure to the motor to swing the carrier to the rearward position.

ssure to the motor to swing the car-
a check engaging said rack to hold
compressed on the termination of
and an ejector in operative engage-
said check to trip it on the inser-
charge, whereby the valve is shifted
pressure to the motor to swing the
closed position.

combination of a gun, a breech-
carrier pivoted thereon, a motor for
said carrier, a valve for admitting
id to opposite sides of said motor to
means operating said valve, a check
id means inoperative when the car-
ing open, and an ejector engaging
and tripping it when the charge is

gun, the combination of a breech-
its carrier coöperating as a motor
the breech-block, with a motor for
the carrier, passages for motive
igh the carrier from one motor to
and a valve controlling the supply
fluid to said motors.

gun, the combination of a breech-
a carrier one of which has a groove
a plane at right angles to the axis
ck and the other having a lug or
ring said groove or way, thereby
breech-block motor, a bracket on
motor for swinging the carrier, a
r motive fluid formed in the car-
xtending from the breech-block mo-

carrier-motor and a valve for con-
e flow of motive fluid to said motors.

gun, the combination of a breech-
its carrier coöperating as a motor
the block, with a bracket on the
rating with the carrier as a motor

the carrier, a motive-fluid passage
in the metal of the carrier from the
ck to the carrier-motor, and a valve

aving a partially-cylindrical hub
ial opening and a peripheral abut-
a breech-block carrier partially
said hub and having an abutment
site the abutment on the hub, the
on the carrier forming a movable
otor-chamber, and a valve in said
ing admitting motive fluid to said
mber.

combination of a gun, and a bracket
aving a partially-cylindrical hub
ial opening and a peripheral abut-
a breech-block carrier partially
said hub and having abutments on
ides of the abutments on the hub,
ent on the carrier forming a mov-
espectively to two motor-chambers,
e in said axial opening admitting
d to said chambers.

combination of the gun, the breech-

block and its operating-motor, with the car-
riage, the recoil-cylinder thereon, and the pis-
ton in said cylinder, with connections convey-
ing fluid-pressure from one side of said piston
to the motor, and other connections convey-
ing the exhaust from said motor to the other
side of said piston.

30. The combination of the gun, the breech-
block, its operating-motor, the carriage, the
recoil-cylinder thereon, the piston in said cyl-
inder, with rigid connections conveying fluid-
pressure from one side of said piston to the
motor, and other rigid connections conveying
exhaust from said motor to the other side of
said piston.

31. The combination of the gun, the breech-
block, the carrier, the carrier-operating mo-
tor, the carriage, the recoil-cylinder thereon,
and the piston in said cylinder, with connec-
tions conveying fluid-pressure from one side
of said piston to said motor, and other connec-
tions conveying the exhaust from said mo-
tor to the other side of the piston.

32. The combination of the gun, the breech-
block and its motor, the carrier and its motor, 9c
the gun-carriage, the recoil-cylinder thereon,
and the piston in said cylinder, with connec-
tions conveying fluid-pressure from one side
of said piston to one of said motors, other
connections conveying the exhaust from the 95
other motor to the other side of said piston,
and a passage for fluid-pressure between the
motors.

33. The combination of a gun, a recoil-cyl-
inder having a motive fluid therein, a breech-
block, a motor for opening and closing the
breech-block, and connections passing the motive
fluid through the motor for operating the
block to open and close the breech.

34. The combination of a gun, a gun-car-
riage, a source of motive fluid thereon, a
breech-block, a motor for operating the block
to open and close the breech, and means con-
ducting the motive fluid through said motor
for operating said block to open and close the 110
breech.

35. The combination of a gun, a gun-car-
riage, a recoil-cylinder having a motive fluid
therein placed under pressure upon the dis-
charge of the gun, a breech-block, a motor 115
through which motive fluid is passed to op-
erate the block to open and close the breech,
and means conducting the motive fluid from
the cylinder through said motor for operating
the block to open and close the breech.

36. The combination of a gun, a source of
motive fluid placed under pressure by the dis-
charge of the gun, a breech-block carrier mov-
able toward and from the breech, a motor for
operating the carrier in both directions, and
means conducting the motive fluid from its
source through the motor for swinging the
carrier in both directions.

37. The combination of a gun, a recoil-cyl-
inder containing a motive fluid placed under 130

pressure upon the discharge of the gun, a motor, and a carrier forming an element in said motor and operated directly by said motive fluid.

5 88. The combination of a gun, a recoil-cylinder containing a motive fluid, placed under pressure by the discharge of the gun, a breech-block, a breech-block carrier, means for operating said block and carrier for opening 10 and closing the breech, and connections pass-

ing the motive fluid from the cylinder through said means for both opening and closing breech.

In testimony whereof I have signed this specification in the presence of two subscribing witnesses.

SAMUEL N. McCLEAN
